AQUARIUM COVER

Allan H. Willinger, 56 Gail Drive, New Rochelle, N.Y.

Filed Sept. 6, 1961, Ser. No. 66,622

Term of patent 14 years

(Cl. D91—2)

FIG. 1

FIG. 2

FIG. 3

FIG. 4

FIG. 5

FIG. 6

FIG. 7

I claim:

The ornamental design for an aquarium cover substantially as shown.
